UNITED STATES PATENT OFFICE

GEORGE D. SCHERMERHORN, OF READING, MICHIGAN

CHAIR ELEMENT

Application filed August 19, 1929. Serial No. 386,814.

My invention relates to improvements in the construction of chair structures.

An object is to provide a chair element such as a back or a seat for a chair which seat, if the element is embodied in a seat, possesses the advantages of the slat type of chair seat and additional advantages of strength, durability and simplicity of construction which render it an improvement over the slat type of seat and which possesses advantages in utility and appearance over the slat type of seat and it is here shown as embodied in a seat for a folding chair.

One object is the provision of a seat of this character wherein a ply wood seat section is employed in a seat frame and so constructed and mounted within the frame as to give the maximum amount of strength and durability and which, in addition to possessing certain advantages of the slat type of seat, also is so constructed as to minimize any tendency of the upper veneer ply to rupture or break while in use.

Other objects, advantages and meritorious features of my invention will more fully appear from the following specification, appended claims and accompanying drawing, wherein,—

Fig. 1 is a plan of a chair seat partly in section embodying my invention.

Fig. 2 is a cross-sectional view through the seat taken on the line 2—2 of Fig. 1 and showing a part of the supporting leg structure in dotted outline.

Fig. 3 is a section taken on the line 3—3 of Fig. 1 showing a fragment of the seat.

Fig. 4 is a section taken on the line 4—4 of Fig. 1 showing another fragment of the seat.

In the drawing the improved chair element is shown as embodied in a chair seat. Chair seats have heretofore been formed with wood frames wherein slats were arranged to extend transversely of the seat frame being received within grooves formed in the inner edge of the side frame members and they have been formed of ply wood received as a unit within a groove formed in the side frame members and positioned below the upper surface of the frame of the seat.

I provide a seat wherein a ply wood seat section is employed of a novel kind which is fitted in a novel manner within the usual seat frame so that the seat section is flush with the upper surface of the frame and the upper layer or veneer of ply wood is scored transversely in imitation of seat slats, which scoring accomplishes the useful purpose of seat slats in rendering the seat itself more adaptable for use in serving to retain an occupant therein and which furthermore minimizes any tendency present in the upper ply wood layer to break or rupture while in use and to localize any such break or rupture which might occur in one of the scores where it would not do any harm.

The seat frame comprises a pair of side frame members 10 connected in braced apart relationship and rear frame members 12 and 14 respectively. The side frame members 10 are provided along their inner edges with a groove 16 which registers with and is a continuation of a groove 20 that extends along the inner edge of the front frame member 12 and also a similar groove 22 that extends along the inner edge of the rear frame member 14. These frame members are secured together in a suitable manner such as by pins 24 shown in Fig. 1.

A seat section is provided formed of ply wood and I have here shown three layers indicated as 26, 28 and 30, respectively, arranged in the usual overlying relationship and glued together. The two lowermost layers are formed at their margins as at 32 to be received within the grooves 16, 20 and 22. The layer 28 is formed at its margin with a shoulder 34 which rises above the groove in the frame member and abuts the inner edge of the frame member as shown in Figs. 3 and 4. The uppermost layer 30 is not received within the groove but is fashioned to fit snugly within the frame member abutting the inner edges thereof whereby no strain is placed thereon by the groove in the frame and this upper layer is scored at intervals providing a plurality of parallel spaced apart crosswise scores 36. This scoring of the upper layer causes it to present the appearance of a slat type of seat and renders it somewhat

more flexible and minimizes any tendency of the same to rupture in use or, should such rupture occur, induces the same to occur localized within one of the scores.

5. What I claim is:

1. A chair seat having a frame comprising front and rear frame members connected and spaced apart by side frame members, each frame member provided with a groove extending along its inner edge and forming a continuation of the groove of the adjacent frame members whereby a continuous groove extends about the inner edge of the frame, a ply wood seat section shaped to fit within said frame and having a plurality of plies received within said groove and having at least its uppermost ply not received within the groove but disposed in abutting relationship to the inner edge of the frame above the groove and lying flush with the upper surface of the frame and scored at intervals transversely of the seat.

2. A chair seat having a frame comprising a front and a rear frame member connected and spaced apart by side frame members, each frame member provided with a groove extending along its inner edge and forming a continuation of the groove of the adjacent frame members whereby a continuous groove extends about the inner edge of the frame, a ply wood seat section shaped to fit within said frame and having a plurality of plies received within said groove and having at least its uppermost ply not received within the groove and provided with parallel scores extending crosswise thereof in relatively closely spaced apart relationship.

3. A chair element having a frame comprising end frame members connected and spaced apart by side frame members, said frame provided with a groove extending about its inner edge, a ply wood seat section formed of a plurality of plies at least two of which are received within said groove, one of said plies having a shoulder formed at the margin whereby the lower portion thereof is received within the groove and the upper portion thereof abuts the inner edge of the frame above the groove, and a third ply overlying the last mentioned ply and shaped to fit within the frame, said third ply provided with a plurality of parallel relatively closely spaced scores which render the same more flexible and less apt to rupture.

4. A chair element comprising a frame having side frame members spaced apart by end frame members, said frame having its inner edge cut away providing a recess adapted to receive a panel section, and a plywood panel section seated in the recess formed in the inner edge of the frame flush with the outer face of the frame and having its outermost ply scored in imitation of slats.

5. A ply wood chair element formed of a plurality of plies at least two of which are

fashioned for reception within a groove, one of said plies having a shoulder around its margin, and a transversely scored ply superposed upon the shouldered ply and lying within the confines of said shoulder.

In testimony whereof, I, GEORGE D. SCHERMERHORN, sign this specification.

GEORGE D. SCHERMERHORN.
